UNITED STATES PATENT OFFICE.

GEORGE P. TILTON, OF NEWBURYPORT, MASSACHUSETTS, ASSIGNOR TO THE
TOWLE MANUFACTURING COMPANY, OF SAME PLACE.

DESIGN FOR A HANDLE FOR SPOONS, &c.

SPECIFICATION forming part of Design No. 23,557, dated August 14, 1894.

Application filed July 21, 1894. Serial No. 518,280. Term of patent 7 years.

To all whom it may concern:

Be it known that I, GEORGE P. TILTON, of Newburyport, in the county of Essex and State of Massachusetts, have invented and 5 produced a new and original Design for a Handle for Spoons, Forks, and Similar Articles, of which the following is a specification.

Reference is to be had to the accompanying drawings, forming a part of this specification, in which—

Figure 1 represents the obverse of a spoon, the handle of which embodies my new design, and Fig. 2 represents the reverse thereof.

The leading feature of my design consists 15 of the ornamentation shown, which is as follows: The obverse and reverse present each a plurality of reed-like members, ranging longitudinally of the handle, following the marginal lines thereof, the reed-like members being crossed diagonally at intervals by bands 20 in crossed form. The top of the handle at the front is ornamented by a central plain

oval figure having a beaded border, and above the oval is a crown figure; while at each side are scrolls, the upper ends of which are helical, while at the lower ends certain of the members diverge in fan-like form above helical members that curve the reverse of those at the top of the scrolls. At the back at the top of the handle, the longitudinal reed-like 25 members terminate in helical scrolls, and in connection with the same appear two leafy branches, the upper ends of which are brought together at the back of the crown figure that forms part of the obverse ornamentation. 30

I claim—

The design for a handle for spoons, forks and similar articles, herein shown and described.

GEORGE P. TILTON.
